Attorney

UNITED STATES PATENT OFFICE

CHARLES A. PURVIS, OF LONG BEACH, CALIFORNIA

MOP

Application filed September 19, 1929. Serial No. 393,719.

This invention relates to improvements in the mop forming the subject matter of U. S. Patent No. 1,653,415, granted to me and Thomas A. Purvis on December 20, 1927. 5 The mop forming the subject matter of this patent comprises a handle, a head secured to the handle, a mop element or cloth, a bar clamping the cloth to the head, and a resilient spreader arranged within the cloth and 10 secured to the clamping bar. The spreader is adapted to normally hold the cloth in longitudinally extended relation with respect to the handle and is adapted to yield to permit either side of the cloth to be brought into full 15 contact with the surface being cleaned.

The present invention has for one of its objects to provide a mop of the character stated wherein the spreader shall be permanently and directly connected to the head and 20 wherein the cloth shall be directly connected to the spreader, whereby to permit a fresh cloth to be substituted for the old one without removing the spreader and in a comparatively short time and with the expenditure of 25 comparatively little energy.

The invention has for a further object to provide a mop of the character stated wherein the spreader shall be rigid and wherein the spreader shall be pivotally connected to the 30 head to permit the cloth to be normally held in longitudinally extended relation with respect to the handle and to permit either side of the cloth to be brought into full contact with the surface being cleaned.

35 The invention has for a further object to provide a mop of the character stated wherein the cloth shall be normally held in longitudinally extended relation with respect to the handle by a spring connected to the head and spreader.

The invention has for a still further object to provide a mop of the character stated which shall be simple, durable, highly efficient and capable of being manufactured and 40 sold at a comparatively low cost.

With the foregoing and other objects in view, the nature of which will appear as the description proceeds, the invention consists in the construction, combination and arrangement of parts hereinafter fully described and

claimed, and illustrated in the accompanying drawing, wherein:—

Figure 1 is a view partly in section and partly in elevation of a mop constructed in accordance with the present invention; 55

Figure 2 is a view in side elevation of a mop with the cloth in contact with the surface being cleaned;

Figure 3 is a view partly in elevation and partly in section of the handle, head, spreader and spring of the mop, and 6

Figure 4 is a view of the cloth as it appears when detached from the spreader and when viewed from its upper edge. 61

Referring in detail to the drawing, 1 designates the handle, 2 the head, 3 the spreader, 4 the cloth and 5 the spring of the mop.

The handle may be made from wood or other material and it may be of any desired or required length. The head 2 consists of a 70 pair of arms 2^a, which are secured to opposite sides of the lower end portion of the handle 1 by elements 6.

The arms 2^a extend in downwardly diverging relation from the handle 1, and are 75 provided at their lower ends with parallel pivot lugs 7. The arms 2^a are made of metal, and are connected slightly below the handle 1 by a tie pin 8.

The spreader 3 is of substantially rectangular formation and is made from a single length of stout wire which, after being formed to provide the spreader, has its ends secured together by a coupling sleeve 9. The spreader 3 comprises a top bar 3^a, side bars 3^b and a bottom bar 3^c, and it is pivotally connected to the head 2 through the medium of pivot lugs 7 and top bar 3^a. The top bar 3^a is offset upwardly to provide a crank 10, which normally occupies a position 85

between the arms 2^a and which is connected to the arms by the spring 5. The spring 5 is secured at its upper end to the tie pin 8 and is secured at its lower end to a collar 11 mounted upon the crank 10. The top bar 3^a and side bars 3^b are extended to provide shoulders 12 which are located at the top corners 90

of the spreader 3 and extend laterally therefrom. The cloth 4 is in the form of a casing which is opened at its side edges, as at 4^a 100

and partly at its top edge, as at 4^b. The cloth 4 may be readily slipped on or off of the spreader 3, and it is secured against lateral displacement by the closed end of its slot 4^b which contacts with the outer side of one of the pivot lugs 7, and by tapes 13 which are secured to the walls of the slot 4^b and tied together with their knot 13^a contacting with the outer side of the other pivot lug 7.

The tapes 13 and tapes 14, which are secured to the end walls of the slot 4^b outwardly beyond the tapes 13 and connected, as at 14^a, serve to close that portion of the slot 4^b located outwardly beyond that pivot lug 7 with which the knot 13^a contacts. As the top edge of the cloth 4 is closed outwardly beyond the pivot lugs 7, as the entire bottom edge of the cloth is closed, and as these closed edges contact with the spreader bars 3^a and 3^c, the cloth is held against longitudinal displacement from the spreader.

From the foregoing description, taken in connection with the accompanying drawing, it will be understood that the spreader 3 is pivotally connected to the head 2, that it maintains the cloth 4 in outspread condition, and that the spring 5 yieldingly maintains the spreader and cloth normally at a longitudinally extended position with respect to the handle 1. It will be further understood that the handle 1 and cloth 4 may be moved into any angular position necessary to arrange either side of the cloth in full contact with the surface to be cleaned, and that rigidity of the spreader and the upward pressure exerted upon the crank 10 by the spring 5 will maintain the cloth 4 in full contact with the surface.

40 While I have described the principle of the invention, together with the structure which I now consider the preferred embodiment thereof, it is to be understood that the structure shown is merely illustrative and that such changes may be made, when desired, as fall within the scope of the invention as claimed.

I claim:—

1. A mop comprising a handle, a spreader pivotally connected at its upper end to the handle and provided at said end with a crank, a contractile spring connected at one end to the crank and connected at its other end to the handle at a point above the crank, and a cloth mounted on the spreader.

55 2. A mop comprising a handle, a spreader frame of substantially rectangular contour and having one of its bars provided with a crank, means pivotally connecting the frame to the handle through the medium of said bar thereof, a contractile spring connected to said crank and means, and a cloth arranged on the frame.

60 3. A mop comprising a handle, arms extending in downwardly diverging relation from the handle and provided with pivot lugs,

70 a spreader frame of substantially rectangular contour having its top bar passing through the pivot lugs and provided between said arms with a crank, a contractile spring secured to the crank and to said arms, and a cloth applied to the frame.

75 4. A mop comprising a handle, a spreader, means connecting one end of the spreader to the handle, the spreader extending laterally in opposite directions beyond said means, a cloth in the form of a casing surrounding the spreader with its end edges in contact with the ends of the spreader, the casing having its lateral edges open and provided at its upper edge with a slot receiving said means and extending from one lateral side of said means to and through the remote lateral edge of the casing, and means releasably closing that portion of the slot located at the opposite lateral side of said means.

80 In testimony whereof I hereunto affix my signature.

CHARLES A. X PURVIS.
